UNITED STATES PATENT OFFICE.

CLAES WM. BOMAN, OF NEW YORK, N. Y., ASSIGNOR TO THE EAGLE PENCIL COMPANY, OF SAME PLACE.

REVERSIBLE TIP FOR LEAD-PENCILS, &c.

SPECIFICATION forming part of Letters Patent No. 364,473, dated June 7, 1887.

Application filed June 20, 1886. Serial No. 206,737. (No model.)

To all whom it may concern:

Be it known that I, CLAES WM. BOMAN, of the city, county, and State of New York, have invented a certain new and useful Improvement in Reversible Tips for Lead-Pencils, Pencil-Point Protectors, &c., of which the following is a specification.

My invention has relation to what is commonly known as a "reversible tip" for lead-pencils, pencil-point protectors, and like articles—that is to say, a removable tip (adapted usually to hold a stick of rubber or other erasive material) combined with a socket formed in or attached to the pencil or other article; into which socket either end of the tip can be inserted, according as it is desired to cover or expose the rubber or other material or article carried by said tip. Such a device, broadly considered, is not new, but has been long on the market and in use; and it has also been customary to so form the device that the two parts—the removable and reversible tip and the socket—may be detachably fastened together, such fastening having heretofore usually been accomplished by forming on the tip a screw-thread to screw into a corresponding thread formed in the socket.

My improvement has relation more particularly to the means for fastening the two parts together, and can best be explained and understood by reference to the accompanying drawings, in which—

Figure 1 is a side elevation of a device embodying my invention in its preferred form, said device being applied to the end of a lead-pencil. Fig. 2 is a longitudinal central section of the same. Fig. 3 is a perspective view of the two parts—the socket and the reversible tip—detached from each other.

The device shown in the drawings is one intended to be attached to a lead-pencil. The sheet-metal tube A, which constitutes the socket, is therefore fitted and secured upon one end of a lead-pencil, C. This socket-tube is split or slit on each side for a portion of its length, as seen at a, the object being to make it capable of expanding to admit the tip B. The slits a virtually divide the tube for a por-

tion of its length into jaws which are spring-closing. The outer ends of these jaws are bent or inclined inwardly, as seen at b, with a view to enter a corresponding annular groove in the tip B. This tip is sheet metal, cylindrical in form, and of any usual construction, so far as concerns that portion of it which receives or carries the rubber or other article with which it is desired to provide the tip. In the present instance the tip contains a cylindrical stick, d, of rubber or erasive material, being for this purpose made tubular with one end closed. The tip is of such size or diameter, as compared with the socket, that when inserted therein it will slightly expand the jaws or split parts of the socket. Consequently, when the tip is inserted far enough, the jaws will meet and snap into the annular groove or recess e, formed in the body of the tip, the two parts being thus fastened together tightly enough to prevent them from coming apart under any ordinary conditions of use, but at the same time not positively enough to prevent them from being pulled apart by hand.

The ends of the tip are rounded or beveled to permit of their easy insertion into the socket, and I provide two grooves, c, one on each side of the central head, c', so that the reversible tip may be inserted and held in place either with the rubber exposed, as in Fig. 1, or with the rubber covered and contained within the socket, as in Fig. 2.

Having described my improvement, what I claim is—

The tube A, split as at a, to form spring-closing jaws, having inwardly-turned ends b, in combination with the rubber-containing tip B, provided with the annular bead c' and the two annular grooves c, one on each side of said bead, as herein shown and described.

In testimony whereof I have hereunto set my hand this 24th day of June, 1886.

CLAES WM. BOMAN.
